UNITED STATES PATENT OFFICE.

FRANK CHIAFFARELLI, OF NEW YORK, N. Y.

TRUMPET MUTE.

Application filed May 1, 1923. Serial No. 635,982.

To all whom it may concern:

Be it known that I, FRANK CHIAFFARELLI, a citizen of the United States, residing at Bronx, New York, in the county of New York and State of New York, have invented certain new and useful Improvements in Trumpet Mutes; and I do declare the following to be a full, clear, and exact description of the invention, such as will enable others skilled in the art to which it appertains to make and use the same.

This invention relates to an improved mute for use in connection with wind musical instruments, but it has more particular reference to a mute which is especially designed for use in the bell of a cornet, trumpet, trombone or the like.

The principal object of the invention is to provide an improved form of mute which may be referred to as a convertible mute due to the fact that it is of such construction that by proper manipulation without removing it from the bell of the horn, it can be varied to change the quality or intensity of the tonal waves issuing from the horn to produce varied effects.

More specifically speaking, it is an object of the invention to provide a mute which is especially designed for insertion in the bell of a trumpet, this mute being similar to the one commonly employed, but being provided with a series of openings through which the sound waves may pass and these openings being controlled by a valve operated from the exterior of the horn, so that they can be entirely closed to produce the full muted effect or opened to the desired degree to produce a more open and sombre tone resembling that of a French horn.

Other objects and advantages of the invention will be apparent during the course of the following description.

In the accompanying drawings forming a part of this specification and in which like numerals are employed to designate like parts throughout the same:

Figure 1 is a longitudinal section of the bell of a trumpet showing the improved mute inserted therein with the openings partially opened.

Figure 2 is a central vertical longitudinal section taken on the line 2—2 of Fig. 1.

Figures 3 and 4 are transverse sections taken on the lines 3—3 and 4—4 respectively of Fig. 2.

As seen in the drawing, the preferred form of the invention comprises a truncated-conical body 1 which is open at its inner small end and closed at its opposite end. This part of the mute is substantially a duplicate of the form of mute now commonly employed by cornetists and the like. When the common type of mute is employed, it gives a full muted effect to the tone and since it is found desirable to vary this tone color while playing without removing the mute from the horn, I have conceived of a form of mute which, as before stated, permits this result to be accomplished. In carrying out this end, I simply form the truncated-conical body 1 at a point between its ends with a row of circumferentially spaced openings 2 and when the full muted effect or tone color is desired, these openings are entirely closed by an outer conical sleeve 3 which surrounds the body 1 and is stationary with respect thereto to permit this result to be obtained. The sleeve 3 is comparatively long and is provided between its ends with openings 3^a with which the opening 2 in the body 1 are adapted to be registered when a more full tone is desired. At its inner end, this conical sleeve 3 abuts a bushing or shoulder 4 on the inner end of the aforesaid body 1 and this sleeve 3 is provided between its ends with the usual cork lugs or spacers 5 which are adapted to bind against the inner wall of the bell of the horn.

In practice, the mute is inserted in the bell of a trumpet or the like in the usual way so that the cork lugs 5 bind against the inner wall of the bell. If it is desired to play a strain in pianissimo style, the closed inner body 1 is grasped while the device is in the horn and rotated relatively to the sleeve 3 to close the openings in these parts. Thus, the full muted effect can be had. If it is desired to increase the intensity of the sound waves slightly or to produce a more open tonal effect, the body is grasped and rotated to uncover the openings to the desired degree, thus permitting a greater volume to be produced. When the openings in the

mute are fully uncovered, the instrument does not have its original tone quality, but has a slightly muted effect and it may be accurately stated that at this time the tone 5 resembles slightly that of a French horn.

It is to be noted that a mute of the construction described will be found particularly advantageous in use, in that the adjustment can be made while the mute is in position so that if desired a few bars of any strain can be rendered more effective with the full muted tone and succeeding bars made more effective with a more open tone, this result can well be obtained. Furthermore, in a small combination of instruments 10 where the original trumpet tones would be found too loud, the "French horn effect" can be produced to good advantage. These and other advantages and features of the 15 invention have doubtless been made apparent from the foregoing description and a more lengthy description is therefore deemed unnecessary. It is also to be noted that the conical bodies from which the mute 20 is formed are of such a diameter that the entire mute is substantially confined within the bell of the instrument. Hence, instead of the sound waves being ejected directly 25 into the atmosphere, they are projected against the surrounding wall of the bell to insure the desired resonant tone production.

As before indicated, the mute is equally well adaptable for use in connection with 30 trombones, and in order to adapt it for this purpose it will simply be increased in size to fit the bell of this respective form of instrument.

Since probably the best results may be obtained with the construction and arrangement herein shown and described, this is taken as the preferred embodiment of the 35 invention. However, I wish it to be understood that minor changes coming within the

scope of the invention as claimed may be resorted to if desired.

45

I claim:

1. A mute comprising a truncated conical body having an unobstructed interior and being closed at its outer end, open at its opposite end, and provided between its ends 50 with a row of circumferentially spaced openings, and a fixed valve sleeve with which said body is associated for controlling the passage of sound waves through said openings.

2. A mute of the class described comprising a truncated-conical open-ended sleeve provided between its ends with a row of circumferentially spaced openings and equipped adjacent its inner end with circumferentially spaced lugs to frictionally engage the bell of the horn, and a hollow truncated-conical body rotatable within said sleeve, said body being closed at its outer end, open at its inner end, and provided in 60 its conical walls between its ends with a row of circumferentially spaced openings positioned to register with the corresponding openings in the sleeve.

3. In a mute for trumpets and analogous 70 musical instruments, a pair of inner and outer conical members, the inner rotatable with respect to the other and provided between their opposite ends with openings positioned to register with each other, one of said bodies being closed at its outer end to permit the sound waves to escape through said openings, and means whereby said bodies are held in the instrument to position said openings inwardly from the end 75 of the bell when the mute is inserted in the instrument.

In testimony whereof I have hereunto affixed by signature.

FRANK CHIAFFARELLI.
